[57] CLAIM

The ornamental design for an adjustable boat chair, as shown and described.

DESCRIPTION

FIG. 1 is rear perspective view showing the features of the adjustable boat chair with the cushion in an exploded condition; and,

FIG. 2 is a rear perspective view showing the features of the adjustable boat chair with the cushion in the installed condition.

The left side of the adjustable boat chair is a mirror image of that shown in FIGS. 1 and 2. The portions of the adjustable boat chair as seen from the front which are not shown in the drawing views form no part of the claimed design.
